UNITED STATES PATENT OFFICE

152,618

DESIGN FOR A SOAP HOLDER

Everett L. Kibler, Pittsburgh, Pa.

Application July 31, 1946, Serial No. 132,121

Term of patent 14 years

(Cl. D4—3)

To all whom it may concern:

Be it known that I, Everett L. Kibler, a citizen of the United States, residing in Pittsburgh, in the county of Allegheny and State of Pennsylvania, have invented a new, original, and ornamental Design for Soap Holder, of which the following is a specification, reference being had to the accompanying drawing forming part thereof.

I claim:

The ornamental design for a soap holder, as shown.

EVERETT L. KIBLER.
